DESIGN FOR A COMBINED BIRD CAGE AND STAND

Earl W. Little and Gertrude Little, Indianapolis, Ind.

Application May 1, 1940, Serial No. 92,060

Term of patent 14 years

To all whom it may concern:

Be it known that we, Earl W. Little and Gertrude Little, citizens of the United States, residing at Indianapolis, in the county of Marion and State of Indiana, have invented a new, original, and ornamental Design for a Combined Bird Cage and Stand, of which the following is a specification, reference being had to the accompanying drawing, forming part thereof.

Figure 1 is a perspective view and Figure 2 a

top plan view of the combined bird cage and stand, showing our new design.

The ornamentation on the opposite side of the cage is substantially the same as that on the side shown.

We claim:

The ornamental design for a combined bird cage and stand, as shown and described.
